Thomas James

UNITED STATES PATENT OFFICE.

THOMAS JAMES, OF BRADDOCK, PENNSYLVANIA.

RAILWAY.

SPECIFICATION forming part of Letters Patent No. 498,274, dated May 30, 1893.

Aplication filed May 11, 1892. Serial No. 432,671. (No model.)

To all whom it may concern:

Be it known that I, THOMAS JAMES, of Brad-
dock, in the county of Allegheny and State of
Pennsylvania, have invented a new and use-
ful Improvement in Railways, of which the
following is a full, clear, and exact description,
reference being had to the accompanying
drawing, forming part of this specification, in
which the figure illustrates in side elevation
10 a portion of an inclined railway provided with
my improved tilting bridge.

It consists in the construction and arrange-
ment of the parts as hereinafter more fully
described and set forth in the claim.

15 In the drawing, in which similar numerals
indicate corresponding parts, 2 indicates a
portion of the track of an inclined railway,
above which upon a pair of side standards 3
is pivoted the swinging bridge 4. This bridge,
20 which is in the form of a truss, is trunnioned
at its center as shown, and provided with lon-
gitudinally-extending rails which are in line
with the track rails and are beveled at each
end so as to direct the car from or to the track-
25 rails. Stops 11 are provided at either end of
the bridge which serve to support the ends of
the bridge and prevent bending of the be-
veled ends of the rails.

5 represents the stand or support for the
30 car when at its uppermost position, and 6 the
driving engine which operates the cars by
means of the winding drum 7. The cars 8
and 9 are connected by the rope 10 in the
usual manner, so that as one car moves up
35 the incline the other descends, the drawing
showing in full lines the car 9 descending and
just passing upon the bridge, while the car 8
is ascending and passing beneath the raised
lower end of the bridge. As the car 9 de-

scends and reaches the center of the bridge, it 40
automatically tilts the same into parallelism
with the track, as shown in dotted lines, the
car 8 then being beneath the trunnions. As
the car 9 descends still farther the bridge tilts
downwardly until its rails rest at their lower 45
ends upon the track rails, when it then moves
downwardly upon the same to its lowermost
position, the car 8 passing to the upper sta-
tion. When the winding drum is operated
in the opposite direction, the car 8 may ride 50
over the bridge, or the same may be tilted
back into the position of the figure, the car 9
then riding downwardly over the same.

The advantages of my device are apparent.
Only a single track is used where before two 55
tracks were necessary, and thus the cost of
building and keeping in order is generally
reduced.

The device is simple and easily and cheaply
constructed.

It is evident that either car desired may
pass over the bridge, or they may alternate,
and that they may themselves automatically
actuate the bridge or auxiliary devices may
be employed to tilt the same.

What I claim is—

The combination with a track and a swing-
ing bridge supported above the same, of two
cars having a flexible connection with each
other and arranged to automatically operate 70
the bridge; substantially as described.

In testimony whereof I have hereunto set
my hand this 4th day of May, A. D. 1892.

THOMAS JAMES.
